UNITED STATES PATENT OFFICE.

LEWIS FRITZ, OF CHICAGO, ILLINOIS.

PICTURE-FRAME STAND.

1,414,351.

Specification of Letters Patent. Patented May 2, 1922.

Application filed November 30, 1921. Serial No. 518,785.

To all whom it may concern:

Be it known that I, LEWIS FRITZ, a citizen of the United States, and a resident of the city of Chicago, county of Cook, and State 5 of Illinois, have invented certain new and useful Improvements in Picture-Frame Stands, of which the following is a specification.

My invention relates to improvements in 10 picture frame stands and has for its principal object the provision of an improved construction of this character which will be highly efficient in use and economical in manufacture.

15 A further object of my invention is the provision of a picture frame stand, of the character illustrated in the drawings, which can be adjusted to fit various sizes of picture frames.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1 is a front elevational view of the invention;

30 Fig. 2 is a side elevational view of the same;

Fig. 3 is a sectional detail view of the 35 same taken substantially on line 3—3 of Fig. 1;

Fig. 4 is a fragmentary sectional detail view of the same taken substantially on line 4—4 of Fig. 2;

40 Fig. 5 is a fragmentary sectional detail view of the same taken substantially on line 5—5 of Fig. 4;

Fig. 6 is a fragmentary sectional detail view of the same taken substantially on line 6—6 of Fig. 2; and

45 Fig. 7 is a perspective view of one of the end filler blocks embodied in the invention.

The preferred form of construction as 50 illustrated in the drawings comprises a base member 10 which, as shown, is in the form of a sheet metal box-like structure. Formed in the top of the base member 10 is a dove-tailed groove 11 which extends longitudinally with respect thereto, as shown in Figs.

3 and 5. Slidably mounted in the dove-tailed groove 11 is a pair of co-operating supports 12, each of which being provided 55 at their groove-engaging ends with a foot 13 which corresponds in shape and size with the groove 11. It will be found that after mounting the supports 12 in the desired position in the groove 11 that the remaining 60 portion of the groove will be open, into which filler members are mounted to give the base the appearance of a solid construction. The filler members comprise filler blocks 14 which are mounted in the opposite 65 ends of the groove 11 adjacent the outer ends of each of the feet 13 of the supports 12. The filler blocks 14 are constructed so as to tightly engage the surfaces of the groove 11, the arrangement being such so as to prevent the filler blocks from becoming accidentally displaced and to firmly retain the 70 supports in position. A filler member is also mounted in the groove 11, between the inner ends of the feet 13, said member comprising 75 filler blocks 15 and 16, which are also shaped to correspond with the shape of the groove 11, said blocks being also arranged to tightly engage the surfaces of the groove. Fixedly secured to the filler block 16 is a sheet metal 80 tongue 18 which slidably engages a recessed sheet metal member 19 which is fixedly secured to the filler block 15, as shown in Fig. 4. The specific construction so far described provides supports which can easily 85 be adjusted towards and away from each other and firmly retained in any desired position. The filler blocks 14 may be of a construction similar to the construction of the filler blocks 15 and 16 to avoid the necessity 90 of manufacturing end filler members of various lengths to fill the end spaces of the groove 11 when the supports are moved toward or away from each other.

The picture frame receiving members comprise a pair of supporting arms 20 and 21, which are also formed of sheet metal. The lower ends 22 of the supporting arms are rabbeted, as shown, arranged to engage rabbed ends 23 of the supports 12. The supporting arms 20 and 21 are pivotally connected to the supports 12, as shown, in any suitable manner; a screw threaded bolt 24 being provided to firmly secure the support 95 100

ing arms in the desired tilted position on the supports 12. The upper portions of the supporting arms 20 and 21 are provided with longitudinally extending recesses 25, of appropriate length, into which a picture frame 26 is mounted. Mounted in the sides of each of the supporting arms 20 and 21, adjacent the top ends thereof, is a buckled spring leaf 27 which is arranged and adapted to frictionally engage the side edges of the picture frame 26, the arrangement being such that the spring members 27 will retain the picture frame in any desired position when mounted in the recesses 25. This arrangement also permits picture frames of various lengths to be positioned in the recesses 25. When a large picture frame, such as is shown in Fig. 1, is positioned in the recesses 25, the lower edge 28 of the picture frame 26 can be permitted to rest upon the top 29 of the lower ends of each of the supporting arms 20 and 21, which are in the form of a box-like structure, as shown.

The preferred form of construction as herein set forth, comprises a picture frame stand which is formed of sheet metal; however, the picture frame stand can be a metal casting or made entirely of wood, as desired.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A picture frame stand including a base; a groove formed in said base and supporting members mounted in said groove, said members being adapted to be adjusted towards and away from each other, said supporting members comprising parts pivotally connected together, one of said parts adapted to receive a picture frame, substantially as described.

2. A picture frame stand including a base; supporting members slidably mounted on said base; and recessed arms pivotally mounted on said supporting members adapted to receive a picture frame, substantially as described.

3. A picture frame stand comprising a base; a groove formed in said base; supporting members mounted in said groove; and arms pivotally connected to said supporting members, adapted to receive a picture frame or the like substantially as described.

4. A picture frame stand comprising ad-

justable supports and recessed arms pivotally connected to said supports adapted to receive a picture frame, there being a seat for said picture frame at the lower extremities of each of the recesses of said arms substantially as described.

5. A picture frame stand comprising a base; supporting members mounted on said base; arms pivotally connected to said supports adapted to receive a picture frame; and means frictionally engaging said picture frame for retaining said frame in position on said arms, substantially as described.

6. A picture frame stand comprising a base; a groove formed in said base; picture frame supports mounted in said groove; and means frictionally engaging the edges of said picture frame for retaining said frame in position on said supports.

7. A picture frame stand comprising a base; a groove formed in said base and extending longitudinally with respect thereto; supporting means mounted in said groove; arms pivotally mounted on said supporting means adapted to receive a picture frame; and a buckled leaf spring carried by said arms adapted to frictionally engage the edges of said frame retaining said frame in position on said arms, substantially as described.

8. A picture frame stand comprising a base; a dove-tailed groove formed in said base; supports mounted in said groove; and arms pivotally mounted on said supports, there being recesses formed in said arms for the reception of a picture frame, substantially as described.

9. A picture frame stand comprising a base; a groove formed in said base; recessed picture frame supports mounted in said groove; and an adjustable filler member mounted in said groove between said supports, substantially as described.

10. A picture frame stand comprising a base; a groove formed in said base; supports adjustably mounted in said groove; a filler member mounted in said groove between said supports; and arms pivotally mounted on said supports adapted to receive a picture frame, substantially as described.

11. A picture frame stand comprising a base; a groove formed in said base; oppositely arranged supports slidably mounted in said groove; a filler member adjustably mounted in said groove between said supports; arms pivotally connected to said supports adapted to receive a picture frame; and means carried by said arms for frictionally engaging said frame retaining said frame in position on said arms, substantially as described.

12. A picture frame stand comprising a base; a groove formed in said base; supports mounted in said grooves; a filler mem-

ber adjustably mounted in said groove; and buckled leaf springs carried by said supports adapted to frictionally engage the side edges of a picture frame, substantially as described.

13. An article of the class described comprising a hollow base; a groove formed in said base and extending longitudinally with respect thereto; oppositely arranged supports mounted in said groove, there being recesses formed in the upper portion of said supports adapted to receive a picture frame; and an adjustable filler member mounted in said groove between said supports, substantially as described.

14. An article of the class described comprising a hollow base; oppositely arranged supports adjustably mounted on said base; arms pivotally connected to said supports, there being recesses formed in the adjacent faces of said arms for the reception of a picture frame; and resilient means frictionally engaging the side edges of said picture frame for retaining said frame in position on said arms, substantially as described.

15. An article of the class described comprising a base; a groove formed in said base; supports mounted on said base, there being a foot formed on each of said supports adapted to slidably engage said groove; arms pivotally connected to said supports; recesses formed in the upper portion of said arms for the reception of a picture frame; and a buckled leaf spring carried by each of said arms in said recesses adapted to engage the side edges of said picture frame, substantially as described.

16. An article of the class described comprising a hollow metallic base; a groove formed in said base and extending longitudinally with respect thereto; oppositely arranged supports mounted on said base, there being a foot formed on each of said supports adapted to slidably engage said groove; an adjustable filler member mounted in said groove between the feet of said supports; a filler block mounted in said groove adjacent the outer end of the feet of said supports; arms pivotally connected to said supports; recesses formed in the upper portion of said arms for the reception of a picture frame; and a leaf spring carried by each of said arms adapted to engage the side edges of said picture frame for retaining said picture frame in position on said arms, substantially as described.

17. A picture frame stand of the class described comprising a base; a groove formed in said base; and supporting members adjustably mounted on said base, there being a foot formed on each of said supporting members adapted to engage said groove, substantially as described.

18. The combination with a base, of a groove formed in said base; a support ad-

justably mounted in said groove; and an arm pivotally mounted on said support, there being a recess in said arm for the reception of a picture frame, substantially as described.

19. The combination with a base, of a groove formed in said base; oppositely arranged supports adjustably mounted in said groove; arms pivotally connected to said supports; and means for frictionally engaging the side edges of a picture frame carried by said arms, substantially as described.

20. The combination with a hollow base, of a groove formed in said base; oppositely arranged supports mounted on said base, there being a foot formed on each of said supports adapted to slidably engage said groove; and means pivotally mounted on said supports adapted to receive a picture frame or the like, substantially as described.

21. A picture frame stand including a base; pivotally mounted extensible picture frame supporting members mounted on said base; and means carried by said supporting members adapted to frictionally engage the side edges of a picture frame, substantially as described.

22. A stand of the class described including a base, picture frame supports on said base, said supports comprising upper and lower parts pivotally connected together, there being recesses formed in the upper parts of said supports for the reception of a picture frame, and means arranged in said recesses and frictionally engaging the side edges of said frame for adjustably supporting said frame in said recesses.

23. A stand of the class described including a base, picture frame supports on said base, said supports being adapted to be adjusted longitudinally with respect to said base, and means frictionally engaging the side edges of a picture frame for adjustably supporting said picture frame on said supports.

24. A stand of the class described including a base, picture frame supports, there being recesses formed in said supports for the reception of a picture frame, there being a seat formed at the lower extremities of said recesses for said frame, and means arranged in said recess for adjustably supporting said picture frame therein.

25. A stand of the class described including a base having a longitudinally extending groove formed therein, picture frame supports on said base, a foot formed on each of said picture frame supports and engaging said groove, and means carried by said support for adjustably supporting said picture frame on said supports.

26. A stand of the class described including a base having a longitudinally extending groove formed therein, picture frame

supports on said base, there being a foot formed on each of said supports and engaging said groove, there being recesses formed in the upper portions of said supports for 5 the reception of a picture frame, and a seat formed at the lower extremities of each of said recesses for said frame.

In testimony whereof I have signed my name to this specification in the presence of two subscribing witnesses.

LEWIS FRITZ.
